UNITED STATES PATENT OFFICE.

THOMAS F. BROWDER, OF GREENFIELD, OHIO.

FIRE-ESCAPE.

SPECIFICATION forming part of Letters Patent No. 668,856, dated December 18, 1900.

Application filed April 14, 1900. Serial No. 12,867. (No model.)

To all whom it may concern:

Be it known that I, THOMAS F. BROWDER, a citizen of the United States, residing at Greenfield, in the county of Highland and State of Ohio, have invented certain new and useful Improvements in Fire-Escapes; and I do hereby declare the following to be a full, clear, and exact description of the invention, such as will enable others skilled in the art to which it appertains to make and use the same.

This invention belongs to that class of devices designed to provide an escape for persons from a burning building by jumping when no other safe means of exit presents itself, and in this connection it is intended particularly as an improvement on the device patented by me August 2, 1887, No. 367,362.

The invention relates more particularly to the joint between the sections of the frame, the connection between the blanket and the hangers, and to the reinforcement of the blanket, whereby the device is rendered more desirable and safe without adding appreciably to the cost or weight.

For a full description of the invention and the merits thereof and also to acquire a knowledge of the details of construction of the means for effecting the result reference is to be had to the following description and the drawings hereto attached.

While the essential and characteristic features of the invention are necessarily susceptible of modification, still the preferred embodiment thereof is illustrated in the accompanying drawings, in which—

Figure 1 is a perspective view of the fire-escape constructed in accordance with and embodying the principles of the invention. Fig. 2 is a perspective view of the frame folded and stripped of the blanket and hangers. Fig. 3 is a detail view in perspective of the parts of the joint separated. Fig. 4 is a detail perspective view of the key. Fig. 5 is a detail view of a modified form of link between the blanket and hanger. Fig. 6 is a detail view in elevation of the link shown in Fig. 5.

Corresponding and like parts are referred to in the following description and indicated in all the views of the drawings by the same reference characters.

In its general construction the fire-escape

comprises the frame 1, blanket 2, and yielding connections between the frame and blanket. The frame is of sectional construction, so as to fold in a small space, and may be of any configuration and size, according to the general outline of the device. In the preferable construction the frame is of circular outline and is composed of two sections or halves hinged together, so as to fold one upon the other. The members of the frame are reinforced at their terminals, as shown at 3, and ears or lugs project from the reinforcements at diametrically opposite points and are adapted to receive the fastenings, by means of which the sections of the frame are secured when unfolded or extended, so as to lie in the same plane. The topmost ears are connected by a pin or bolt 4 and constitute the hinge members between the sections of the frame, and the lowermost ears are adapted to receive a key 5 when the sections of the frame are unfolded, so as to prevent their closing when in operation. The openings 6 in the lower set of ears are elongated in the plane of the frame when extended to admit of the passage of the lug 7, formed upon one side of the terminal portion of the key, and which lug after passing through the registering openings 6 is caused to sit crosswise thereof by turning the key 5 so as to occupy a position at a right angle to the plane of the frame. The end portion of the key carrying the lug 7 is reduced, as shown at 8, and the shoulder formed at the inner end of the reduced part 8 limits the movement of the key when inserting it through the openings 6, and after the lug 7 has cleared the ears and the key is turned it is prevented from casual displacement by the said lug 7 and shoulder at the base of the part 8. The joint is stiffened and strengthened by means of a projection 9 at the end of one section entering a socket 10, provided in the end of the adjacent section, said projection overlapping the joint formed between the sections of the frame and preventing relative movement thereof in any direction. The projection 9 is of rounded form, which is best adapted to cause the sections of the frame to aline and admit of their free folding and unfolding when extending or closing the frame.

The blanket 2 may be of canvas, duck, or any stout textile, and its outer edge is rein-

forced and is provided at intervals with loops 11 to receive the means forming the yielding connection between the blanket and the frame. A supplemental blanket 12 is placed 5 upon the blanket 2 and is padded and preferably composed of two plies, between which is interposed a layer of cotton-batting or other packing material, the whole being quilted. This supplemental blanket may be placed 10 loosely upon the main blanket 2 or may be stitched or otherwise secured thereto and is preferably of less diametrical extent and when free of the blanket 2 is connected at its edges therewith by stout elastic strips 13, 15 which assist in a measure in breaking the fall of a person alighting upon the device when jumping from an elevated point. In order that the person may be enabled to alight upon the central portion of the blanket, the latter 20 is provided at its center with a textile 14 of contrasting color to that of the blanket, so as to be readily distinguished at a distance. The purpose of the supplemental blanket 12 is to strengthen the main blanket 2 and materially assist in breaking the fall of the person jumping from an elevation upon the device. 25

The hangers 15 consist of eyebolts or rods having their lower ends threaded to receive 30 nuts 16 and their upper ends bent to provide eyes which receive the rod or bar from which the frame is constructed. A spring 17 is mounted upon each hanger and supports the connection provided between the hanger and blanket. The connection may consist of a 35 single link 18 or a sleeve 19 and link 20, the cross-head being slidably mounted upon the hanger and the link 20 having an end portion fitted to the sleeve and its opposite end portion receiving one of the loops 11. The link 40 18 comprises a loop 21 and an eye 22, the latter receiving a hanger and the loop 21 passing through one of the loops 11. The loop 21 and eye 22 occupy a position at a right angle 45 to each other, whereby the eye 22 is prevented from binding upon the hanger and is adapted to slide freely upon said hanger under the action of the spring 17 and a weight superposed upon the blanket.

50 When the device is not required for immediate service the sections of the frame are folded one upon the other, so as to reduce the appliance within limits for convenience in storage; but when it is required for action the sections of the frame are extended and are held in the same plane by means of a key 55 5. When in position to receive a person jumping from a burning building, the device is grasped by a number of persons catching 60 hold of the frame 1, and in order to prevent injury to the hands and to the person jumping by striking the said frame the latter is clothed or covered by means of a casing 23, of rubber or similar fibrous and yielding material, which is disposed so as not to interfere 65 with the free movements of the hangers, which is essential to ease the shock incident to the

person striking the blanket when alighting thereon.

Within the purview of the invention it is 70 contemplated to dispense with the hinge feature between the sections of the frame, likewise do away with the projection 9, extending across the joints. It is also proposed to have the frame either plain or protected by the 75 application thereto of the covering. The link disclosed in Fig. 5 may be cast or otherwise formed without having the portion between the eye 22 and loop 21 welded or brought together. The inner blanket 12 prevents 80 tearing of the blanket 2 and strengthens and reinforces it. The features just enumerated are of minor importance and may be varied in form and proportion without departing in the least from the spirit of the invention as contemplated and set forth in the 85 claims.

Having thus described the invention, what is claimed as new is—

1. In a fire-escape of the character described, and in combination with the blanket and yielding connections, a sectional frame adapted to fold, and reinforcements applied to the terminals of the sections and adapted to form hinge members, one set of reinforcements having sockets and the other set projections to enter said sockets and overlap the joint formed between the sections, substantially as specified. 90

2. In a fire-escape of the character set forth, 100 and in combination with the blanket and yielding connections, a folding frame having its sections provided at diametrically opposite points with corresponding transversely-apertured ears adapted to overlap, one set of 105 ears constituting a hinge-joint, and a fastening removably fitted to the other set of ears, substantially as set forth.

3. In a fire-escape of the character set forth, 110 and in combination with the blanket and yielding connections, a folding frame having a hinge connection upon one side of its plane and provided upon the other side with ears adapted to overlap and transversely apertured, the openings in the last-mentioned 115 ears being elongated in a direction parallel with the plane of the frame when extended, and a key having an offstanding lug to pass through the elongated opening of the matching ears and adapted to be turned to sit cross-wise thereof, substantially as set forth. 120

4. In a fire-escape of the character described, a folding frame for supporting the blanket and yielding connections, the joint between the sections of the frame comprising 125 a socket and a projection and having relatively upper and lower sets of ears, the upper ears being permanently hinged and the lower ears having transverse openings elongated in a direction parallel with the plane of the 130 frame when extended, and a key having a reduced end portion provided with a terminal offstanding lug to pass through the ears having elongated openings, said key being adapt-

ed to be turned to confine the ears between a lug thereof and the shoulder formed at the base of the reduced end portion, substantially as specified.

5 5. In a fire-escape, and in combination with the frame, blanket and hangers, supporting-springs, links, each comprising an eye and a loop portion and bent intermediate of its ends to throw the eye and the loop approximately 10 at a right angle to each other, the eye portions of the links encircling the respective hangers, and means connecting the loops with the blanket, substantially as specified.

6. In combination with the frame, blanket 15 and hangers, supporting-springs, links connecting the blanket with the hangers and comprising a looped portion and an eye portion disposed relatively at a right angle to

each other, the eye portion being slidably mounted upon the hangers, substantially as 20 specified.

7. In a fire-escape of the character described, a blanket and yielding connections, in combination with a sectional frame having interlocking projections at the joints and 25 upper and lower sets of ears adapted to overlap and transversely apertured, and means connecting the ears by being passed through the registering openings thereof, substantially as described.

In testimony whereof I affix my signature in presence of two witnesses.
